UNITED STATES PATENT OFFICE.

EDMESTON V. THOMAS, OF KANSAS CITY, MISSOURI.

BALANCED SLIDE-VALVE.

SPECIFICATION forming part of Letters Patent No. 416,812, dated December 10, 1889.

Application filed August 20, 1889. Serial No. 321,396. (No model.)

To all whom it may concern:

Be it known that I, EDMESTON V. THOMAS, of Kansas City, Jackson county, Missouri, have invented certain new and useful Improvements in Balanced Slide-Valves for Steam-Engines, of which the following is a full, clear, and exact description, reference being had to the accompanying drawings, forming a part hereof.

10 My invention relates to improvements in slide-valves for steam-engines; and it consists in the novel construction hereinafter set forth and described.

In the drawings, which illustrate the manner of carrying out my invention, Figure 1 is a vertical section of a steam cylinder and chest provided with my improved slide-valve. Fig. 2 is a cross-section of same, taken on line $\alpha\alpha$ of Fig. 1; and Fig. 3 is a detail in perspective 20 of my improved slide-valve.

Referring to the drawings by letter, A represents a steam-chest, provided with my improved slide-valve C, which has a longitudinal opening a located near its top. Communicating with said slot or opening and extending vertically through the top of the valve is opening c , these two openings forming an entrance for the steam from pipe d into chest A. In chests where the steam enters 25 in the side, opening c may be dispensed with, as the steam has ample space to enter between the side of the valve and steam-chest. I provide longitudinal perforation a in order that the valve ends will not present such a broad

surface to the steam while working back and forth.

D is the exhaust-cavity in the under side of the valve.

B is an ordinary cylinder, having steam-ports $g g'$, and $e e$ are extending and overhanging faces formed on the upper portion of the valve, as shown, for the purpose of giving an equal bearing-surface on the upper and lower sides of the valve. By extending the valve to the upper side of the steam-chest an equal pressure is obtained, thus lessening the friction to a minimum and requiring but little power to operate the valve.

The improved valve may be given motion by the ordinary rod h , passing out of the chest by way of a stuffing-box.

Having thus described my invention, what I claim is—

The improved balanced slide-valve having the longitudinal opening a in its body, the extensions $e e$ at opposite ends, vertical opening c in its upper face, communicating with steam-pipe d and opening a , exhaust-cavity D in its lower face, and a valve-rod, in combination with a steam chest and cylinder, substantially as specified.

In testimony whereof I affix my signature in presence of two witnesses.

EDMESTON V. THOMAS.
